UNITED STATES PATENT OFFICE

153,535

DESIGN FOR A PERFUME BOTTLE

Dorothy E. Mackenzie, Greenwich, Conn.

Application March 9, 1948, Serial No. 145,002

Term of patent 7 years

(Cl. D58—8)

To all whom it may concern:

Be it known that I, Dorothy E. Mackenzie, a citizen of the United States, residing at Greenwich, in the county of Fairfield, State of Connecticut, have invented a new, original, and ornamental Design for Perfume Bottle, or which the following is a specification, reference being had to the accompanying drawing, forming part thereof.

In the drawing:

I claim:

The ornamental design for a perfume bottle, as shown.

DOROTHY E. MACKENZIE.
